(57) **CLAIM**

The ornamental design for an electronic cupping device, as shown and described.

DESCRIPTION

FIG. 1 is a front elevational view of an electronic cupping device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof; and,

FIG. 9 is a third perspective view thereof.

The broken lines illustrate portions of the electronic cupping device that form no part of the claimed design.

1 Claim, 9 Drawing Sheets
